UNITED STATES PATENT OFFICE.

JAMES P. QUAM AND WILLARD H. FARR, OF CHICAGO, ILLINOIS, ASSIGNEES TO
UNITED MANUFACTURING & DISTRIBUTING COMPANY, OF CHICAGO, ILLINOIS, A
CORPORATION OF ILLINOIS.

DESIGN FOR A TRANSFORMER CASE.

Application filed October 23, 1922. Serial No. 4,053. Term of patent 14 years.

To all whom it may concern:

Be it known that we, JAMES P. QUAM and WILLARD H. FARR, citizens of the United States, residing at Chicago, in the county of Cook and State of Illinois, have invented a new, original, and ornamental Design for Transformer Cases, of which the following is a specification, reference being had to the accompanying drawing, forming part thereof.

The figure is a perspective view of a transformer case showing our new design.

We claim:

The ornamental design for a transformer case, as shown.

JAMES P. QUAM.
WILLARD H. FARR.
